UNITED STATES PATENT OFFICE

2,468,063

ELECTROMAGNETIC WAVE DIRECTION
INDICATOR

René Hardy, Lyon, France, assignor to International Standard Electric Corporation, New York, N. Y.

Application May 28, 1943, Serial No. 488,876
In France April 18, 1941Section 1, Public Law 690, August 8, 1948
Patent expires April 18, 1961

9 Claims. (Cl. 343—118)

1

The present invention relates to electromagnetic waves direction indicating systems and is an improvement over the system disclosed in my copending patent application filed May 28, 1943, Ser. No. 488,875, now Patent No. 2,440,268 issued April 27, 1948.

The direct reading radio direction finder circuits described in the above mentioned application comprise means for eliminating the 180° inaccuracy in the direction of the indications obtained by eliminating the wrong direction portion of the image produced on the screen of the cathode ray tube used as an indicator. For this purpose, these circuits comprise a device generating short pulses, for example a thyratron relaxation circuit, which is synchronized by the detected envelope curve of the received signals and which at each pulse switches in a vertical antenna or doubt remover circuit. The short duration currents thus furnished by the doubt remover circuit are added and cut off alternately from the detected envelope curve, and the current peaks resulting from the addition of the doubt remover current to the current of the received signals serve to block the cathode beam during part of the scanning through biasing of the control grid of the cathode ray tube, the duration of the blocking being adjusted to about half of the duration of the scanning by a suitable time constant circuit.

It is not however always possible thus to control the grid of a cathode ray tube, particularly when tubes are used in which the luminous intensity of the spot is adjusted by an auxiliary anode. Further, the process as described in the above mentioned application requires a modification of the cathode ray tube circuits that might not be desirable for proper operation of the tube.

Moreover, the application to the grid of the cathode ray tube of an unbalanced voltage such as obtained by the combination of doubt remover pulses and the detected current of the received signals might lead to a self-biasing of the grid the effect of which is to give to this grid a mean biasing varying with the importance of the signal modulating it and consequently causing variation of the luminous intensity of the spot during the time it remains visible.

Consequently, the present invention has among its objects to provide radio direction finding indicator circuits assuring elimination of the 180° inaccuracy in the direction of the indications in the manner described in the said application but not involving fluctuations of the luminosity of the image visible on the screen of the cathode ray

tube and permitting the use of usual control circuits for this tube.

Also, the present invention has likewise among its objects to provide means for assuring, in such circuits, the repetition at a distance of the radio direction finding indications.

According to certain features of the present invention, means permitting the cathode spot to be extinguished during the desired portion of the scanning and comprising the pulse-generating circuit are provided to act on the control circuit of the output stage of the amplifier-receiver and, more specifically, to block the output amplifier tube of the radio direction finding receiver during the desired periods, the output of this amplifier tube being applied only to the deviation elements of the cathode ray tube.

According to other features of the present invention, the pulse-generating circuit controlling the output of the doubt remover circuit controls a circuit generating carrier current modulated in amplitude by the detected envelope curve and the output of which thus modulated and interrupted is transmitted to a transmission line to be applied to one or more distant cathode ray tubes so as to cause a direction finding indication to appear there without direction inaccuracy.

These objects and features, as well as still others, will be explained in detail in the following description given with reference to the accompanying drawings, in which:

Fig. 1 shows schematically a radio direction finder circuit incorporating features of the invention;

Fig. 2 shows a group of curves used in the description;

Fig. 3 shows a type of indication that can be obtained with the circuit shown in Fig. 1; and

Fig. 4 shows a radio direction finder circuit comprising means for repeating the indications at a distance in accordance with features of the invention.

Figure 5 shows a wiring diagram of a thyratron doubt remover circuit for a radio direction finder.

In Fig. 1 is shown an example of a radio direction finder circuit embodying features of the invention, in the case where the indication is obtained by circular scanning in the indicating cathode ray tube. It should be understood however that the invention can be applied to every manner of scanning and to every type of radio direction indication desired.

In the example shown, the crossed wave collecting loops, or directional receiving aerials of any other suitable type, are assumed to be con-

5 nected at 1 and 2 across stators 3 and 4 of a direction finder of usual type whose rotor 5 supplies the input of a receiver comprising high and medium frequency stages 6, a detector stage 7 and a low frequency output amplifier tube or stage 8. Detector 7 controls the grid of output stage 8. These circuits, as well as the other circuits the structures of which do not require a detailed description and which may be well known in themselves, are shown simply as rectangles.

10 In the output circuit of low frequency stage 8 is connected an inductance 9 that rotates around cathode ray tube 10, so as to ensure the driving in continuous and uniform rotation of the cathode beam of this tube, and hence of cathode spot 11 in a circle, such as shown by dotted lines at 12. The speed of rotation of this inductance is synchronized with that of rotor 5 of the radio direction finder. It should be understood however that any other well-known electrostatic or electromagnetic arrangement can be used to rotate spot 11 of indicator tube 10 in synchronism with rotor 5 of the finder (or with the directional receiving antenna if the latter is itself driven in rotation), by means of the output current of amplifier stage 8.

15 So long as the aerials receive no signal, output stage 8 has a constant plate current of a value determined by the biasing of its control grid, and spot 11 is driven in rotation along circle 12, as described. As soon as a signal is received by the aerials, after reception of this signal and amplification in detector 7, the plate current of output stage 8 is modulated and the spot is shifted radially from its circular trajectory.

20 The input circuit of the receiver likewise is supplied by a doubt remover circuit 16. This doubt remover circuit can have any well-known arrangement and is supplied by vertical or all-directional antenna 17. Its output circuit comprises means for bringing high frequency voltages coming from antenna 17 to the input of the receiver with a suitable phase so as to be able to superimpose them on the high frequency voltages coming from the directional antennas with a suitable amplitude. When this doubt remover stage 16 is connected effectively to the receiver, it superimposes in phase or in phase opposition a voltage of constant amplitude on that coming from rotor 5 of the finder.

25 According to a feature of the invention, this doubt remover stage is brought into effective operation only during very short time intervals, as already described in the application above referred to. A relay circuit, for example a thyratron circuit 15, is used to control its operation. An example of the arrangement of such a circuit is disclosed in the said application and is shown in Fig. 5. The arrangement includes a thyratron 12 with a condenser 13 connected in its plate-cathode circuit. The cathode circuit includes the plate-cathode circuit of a constant current pentode 14. When the thyratron is off the condenser charges at a constant rate through the pentode; when the thyratron is turned on by a signal from the amplifier 14 applied to its grid, it discharges the condenser producing the rectangular voltage pulse on its plate. The thyratron is at rest when no signal is detected in a detector circuit 13 connected in shunt with detector 7 at the output of high and medium frequency stages 6 of the receiver. However, as soon as a signal is received by the directional antennas and amplified at 6, owing to the rotation of rotor 5 of the finder, an envelope-curve

30 is obtained showing maxima and minima. This modulated voltage serves to synchronize the discharge of the thyratron which is then brought into operation. During the very short time corresponding to the discharge, the thyratron unblocks doubt remover stage 16 which, during that very short time, applies to the input of the receiver a high frequency voltage coming from antenna 17, in phase or in phase opposition, successively at each half turn of the rotor, with respect to the voltage coming from rotor 5. A buffer or amplifier circuit 14 may be provided between the detector 13 and relay circuit 15.

35 The operation of the system will appear clearly by referring to Fig. 2: In curve A is shown at 20 and 21 the envelope curve detected from the radio direction finder for a full turn of rotor 5 of this finder. This curve consists of two juxtaposed half-sinusoids whose maxima 25 and 27 serve to synchronize discharges 26 and 28 of thyratron relay 15, giving toothed voltages 22, 23, 24, etc., shown in curve B. During the short moment of the discharge of the thyratron, the sudden variation of voltages produced is used to 40 unblock doubt remover stage 16. This stage then generates short voltage pulses that are added algebraically according to their phase to detected curve 20, 21 in the manner indicated in curve C of Fig. 2. In fact, during one half-turn, the 45 current coming from vertical antenna 17 is in phase with the current arriving from rotor 5 of the finder, and "positive" peak 31 is obtained at half-sinusoid 28, and for the other half-turn the doubt remover current is in phase opposition, hence is translated into the appearance of a "negative" peaks 32 at half-sinusoid 20.

50 Curve C thus does not exceed an amplitude 33 except once for each full turn at the moment of "positive" peak 31. This amplitude peak can 40 be used in a time constant circuit of any known suitable structure 18 to furnish a voltage such as voltage 34 of curve D of adjustable duration 36. This adjustable duration voltage 36 serves 45 to control the extinction of the spot of the cathode ray tube 10 through blocking of output stage 8 of the receiver. The voltage produced by time constant circuit 18 is used for the negative biasing of output stage 8 in series with detector circuit 7 so that there be no plate current 55 in stage 8 during a time interval 36 rendered for example equal to one half-period of detected envelope 28-30 from amplitude peak 31 to inverse direction amplitude peak 32. The use of the voltage of circuit 18 as biasing for output stage 8 is made possible by means of a suitable circuit 19 comprising, for example, a tube biased not far from the cut off of its plate current or else a high frequency oscillatory circuit whose amplitude variation is controlled when the 60 voltage of time constant circuit 18 exceeds value 35, curve D, or any other suitable arrangement 65 for giving output stage 8 a negative bias blocking its plate current at each interval 36.

65 In this way, the spot of cathode ray tube 10 will remain in the center of screen 37 of the tube, Fig. 3, while the negative bias applied to output stage 8 will be such that there will be no longer plate current. The spot, which in the absence of signal describes circle 38 on screen 70 37, normally traces, without doubt remover circuit, an image such as 40, 41 and this image does not allow determining directly whether the direction of the received emission is 39 or 43. Time constant circuit 18 giving voltage 34 permits of maintaining the spot in the center of

circle 38 for the duration of a sector 42. Image 40 remains then alone and indicates, without ambiguity, the direction and the sense of the received emission.

It is quite evident that this device is applicable to any other system for indication or deviation of the spot on the screen of the cathode ray indicator. Thus, for example, the fact of acting upon the grid of the output stage of the amplifier and no longer upon the control grid of the cathode ray tube permits of using a rotating potentiometer instead of an inductance mechanically displaced around the tube, which hence allows a complete mechanical separation between the radio direction finder and the indicator. Any mode of scanning and of deformation of said scanning for creating an indication can be used likewise instead of the circular scanning described.

Likewise, it is possible to use the output voltage of stage 8 to modulate a carrier current, which can then serve to transmit to a distance the radio direction finding indication, whereas if the grid of the indicator tube were modulated it would be necessary to use a supplementary transmission. An example of such a system for repeating at a distance the radiodirection finding indication is shown schematically in Fig. 4.

In Fig. 4, the various circuits elements, being of a form already known or described, are not shown in detail. Loops 51 and 52 indicate a directional antenna system, which can be of any suitable type, and are connected to a radio direction finder 53 whose rotor driven by motor 54 supplies the high and medium frequency circuits of receiver 55. These high and medium frequency circuits are followed by a detector circuit 56 and by a low frequency circuit 57 intended for listening, for example, its output supplying a pair of phones or a loud-speaker (not shown). A relaxation circuit, for example, a thyratron circuit 60 is synchronized, as indicated, by connection 61 by means of the envelope curve of the current detected in circuit 56, and the discharge of this thyratron or other synchronized relay permits of bringing into operation, for a very short time, doubt remover circuit 58 which puts in phase or in phase opposition the high frequency current coming from vertical antenna 59 to the input of high frequency circuits 55 of the receiver. The phase and the amplitude of this doubt remover current are adjusted suitably by any well-known method with respect to those of the current coming from the rotor of finder 53. The envelope curve detected in circuit 56 will have, therefore, positive or negative peaks, such as those shown at 31 and 32 in curve C of Fig. 2. These peaks are used in an adjustable time constant circuit 62 to obtain a voltage of an amplitude and of a duration suitable for eliminating or modifying the operation of another circuit provided to distort the amplifier modulation current.

In the arrangement shown, the output of time constant circuit 62 controls suitably, as indicated by connection 64, the modulating portion of a conventional carrier current transmitter 63 of relatively high frequency, 100 kilocycles for example.

On the other hand, the envelope curve coming from detector circuit 56 serves to modulate, in known manner, the amplitude of the carrier current generated by transmitter 63. The operating point of the modulator tube of carrier current transmitter 63 is adjusted so that in the absence

of current detected in circuit 56, the 100-kilocycle carrier current shall have a constant amplitude and so that this amplitude shall diminish in proportion as the detected current increases.

8 The biasing of this tube moreover can be adjusted so that the carrier current shall be cancelled by a diminution up to the cut off of the plate current of the modulator tube by a sufficiently strong detected signal.

10 As described with reference to Figs. 1 to 3, a radio direction finding image can be obtained on the screen of the cathode ray tube by shifting the spot towards the center of the screen through the diminution of the plate current of a tube modulating the scanning voltages applied to said first tube. The spot is in the center when there is no longer plate current in the modulator tube, and through the blocking of this tube it can be kept there during the desired portion of each scanning. In the system shown in Fig. 4, this blocking is obtained by means of time constant circuit 62 which suppresses the output current of transmitter 63 during the useless portion of the scanning produced by the carrier current in the 15 windings of a two-phase distributor 65, consisting, for example, of an inverted radio direction finder whose rotor is driven in synchronism with that of finder 53 by motor 54.

20 The two stators of distributor 65 are connected to transmission lines 68 and 69 to which different local cathode indicators and receivers can be connected. At the near end of transmission lines 68 and 69 can be connected, for example, a local

25 tell-tale equipment comprising a receiver 66 and a cathode ray indicator 67. At the far end of transmission lines 68-69 is shown in Fig. 4 and equipment comprising a receiver 70 and a cathode ray indicator 71 where appears the same image as at indicator 67. The two-phase high frequency voltages distributed over transmission lines 68-69 are detected in receivers 66 and 70 and supply cathode ray tubes 67 and 71. During the useless portion of the image, for example, that comprised in sector 42, Fig. 3, the cathode

30 spot will be kept in the center of the screen, no carrier current being then transmitted to two-phase distributor 65. The other portion of the image, which will appear at both indicators, will give the desired indication of direction and sense.

35 It is evident that the invention is not limited to the embodiment examples shown and described, but rather is capable of numerous modifications and adaptations without exceeding its scope.

40 55 I claim:

1. A radio direction finder comprising a directional antenna, means to rotate the directivity of said antenna, means to receive a signal from said antenna, means to detect said signal, means to produce pulses from portions of said detected signal having a value above a predetermined value, an omnidirectional antenna, means controlled by said pulses to feed signals from said last mentioned antenna into said receiving means during the periods of said pulses only, a cathode ray tube, means to control the spot of said tube in one coordinate of a two coordinate system in accordance with the rotation of said antenna directivity, means to control said spot in the other coordinate by the output of said detecting means, and means to move said spot to a predetermined position for a predetermined time when the output of said detecting means rises above a predetermined value by preventing the output of said

7 detecting means from controlling said spot in said other coordinate.

2. A radio direction finder in accordance with claim 1, in which the two coordinates are polar coordinates.

3. A radio direction finder in accordance with claim 1, in which the means to move the spot on the cathode ray tube to a predetermined position when the output of the detecting means rises above a predetermined value comprises a time constant circuit connected to block out the signal delivered from said detector to said cathode ray tube. 10

4. A radio direction finder in accordance with claim 1, in which the means to move the spot on the cathode ray tube to a predetermined position includes a time constant circuit to hold said spot in said position for approximately one half the rotation of the directivity of the directional antenna. 15

5. A radio direction finder in accordance with claim 1, in which the coordinate system for controlling the spot of the cathode ray tube is a polar coordinate system and in which the spot is moved to the center of the system when the output of the detecting means rises above a predetermined value. 20

6. A radio direction finder comprising a directional antenna, means to rotate the directivity of said antenna, a receiver including selector and amplifier circuits connected to said antenna, a detector connected to said receiver for detecting the low frequency envelope of the output of said receiver, a pulse generating circuit connected to the output of said detector and adapted to produce pulses in synchronism with the peaks of the detected envelope, an omnidirectional antenna, means controlled by said pulses to connect said omnidirectional antenna to said receiver during the periods of said pulses whereby alternate half cycles of the output of said detector are provided with increased voltage peaks, an indicating device arranged for indication in two coordinates, means to control one of the coordinates of indication of said indicating device by the rotation of said directivity of said directional antenna, means to control the other coordinate of indication by the output of said detector, and means to cause said voltage peaks to block out the effect of the output of the detector on said controlling means 25

for said other coordinate of indication for a portion of the cycle of rotation of said directivity of said directional antenna.

7. A radio direction finder comprising a directional antenna, means to rotate the directivity of said antenna, means to receive a signal from said antenna, means to detect said signal, means to produce pulses from portions of said detected signal having a value above a predetermined value, an omnidirectional antenna, means controlled by said pulses to feed signals from said last mentioned antenna into said receiving means during the periods of said pulses only, a transmitter, means to modulate the high frequency of said transmitter by the output of said detecting means, means to reduce the high frequency of said transmitter substantially to zero during predetermined periods of time by said pulses, a pair of output channels for said auxiliary transmitter, means to cause the output of said transmitter in said two channels to be in phase quadrature, means to vary the amplitude of the signal in said two channels in synchronism with the rotational of said directivity of said antenna, the amplitude in said pair of channels being varied inversely, an indicating device located at a remote point, and means to utilize the voltages in said two channels to produce an indication of direction and sense on said indicating device. 30

8. A radio direction finder in accordance with claim 7, in which the means to cause the signal in the two channels from the transmitter to be in phase quadrature is a goniometer in which the two channels are connected to the two stator coils, the output of the transmitter is connected to the rotor coil, and the rotor coil is turned in synchronism with the directivity of the antenna. 35

9. A radio direction finder in accordance with claim 7, in which the indicating device at the remote point is a cathode ray tube. 40
